[57] CLAIM

The ornamental design for a duct access and sensor support door, as shown and described.

DESCRIPTION

FIG 1 is an isometric view of a duct access and sensor support door, showing my new design;
FIG. 2 is a left side elevation view thereof;
FIG. 3 is a right side elevation view thereof;
FIG. 4 is a front elevation view thereof; and
FIG. 5 is a top plan view thereof, the bottom being a mirror image of that shown.

The broken line showing of a portion of a duct in FIGS. 1-3 and an attached sensor in FIG. 5 are for illustrative purposes only and form no part of the claimed design.
